ATTORNEY

UNITED STATES PATENT OFFICE.

VITO GLISCE, OF WATERBURY, CONNECTICUT.

FIRE-EXTINGUISHING SYSTEM.

Application filed February 5, 1924. Serial No. 690,739.

To all whom it may concern:

Be it known that I, Vito GLISCE, a citizen of Italy, and a resident of Waterbury, county of New Haven, and State of Connecticut, have invented certain new and useful Improvements in Fire-Extinguishing Systems, of which the following is a specification.

This invention relates to fire extinguishing apparatus, and more particularly to a manually operated sprinkler system for use in dwelling houses and other buildings.

One object of this invention is to provide a fire extinguishing system of the above nature in which a sprinkler unit is provided in each room of the building, and having means for operating said units either individually or collectively.

A further object is to provide a sprinkler system which may be connected with the ordinary water distributing pipes of the city mains, and which will have a series of individually operated valves for separately delivering water to the sprinkler units in the separate rooms, and a common valve for simultaneously delivering water to all of the sprinkler units in the building.

A further object is to provide a sprinkler system in which the sprinkling action will be localized to the particular part of a building where the fire occurs.

A further object is to provide a system of the above nature which will be very positive and reliable in operation, and which will not depend upon any complicated thermal-operated devices, which are likely to be defective and easily get out of order.

A further object is to provide an apparatus of the above nature which will be simple, inexpensive to manufacture, easy to install and manipulate, and very efficient and durable in use.

With these and other objects in view, there have been illustrated on the accompanying drawing, one form in which the invention may be conveniently embodied in practice.

Fig. 1 represents a side view of one of the sprinkler units shown partly in section.

Fig. 2 is a diagrammatic sectional view of a building in which the fire extinguishing system has been installed.

Fig. 3 is a detailed view of a wing of one of the individually-operated valves for controlling the flow of water to one of the sprinkler units.

Fig. 4 is a view on an enlarged scale of

a set of sprinkler valves and operating nozzles.

Referring now to the drawings in which like reference numerals denote corresponding parts throughout the several views, the numeral 10 indicates a building comprising a basement 11, first floor rooms 12, 13 and 14, and second floor rooms 15, 16 and 17. A supply of water is adapted to be received from the city mains through a pipe 18, and said pipe is connected to a pair of vertical pipes 19 and 20, as clearly shown in Fig. 2. The pipe 19 serves as a main feed pipe for operating the sprinkler units, while the pipe 20 comprises an auxiliary pipe for simultaneously operating the individual valves of the system.

In order to control the flow of water in the auxiliary pipe 20, provision is made of a valve 21 located in any convenient place, such as the basement of the building. On each floor of the building a series of pairs of associated horizontal branch pipes 22 and 23 are connected respectively to the main supply pipe 19 and the auxiliary pipe 20. The pipes 22 are adapted to deliver water to a series of vertical pipes 24 leading to the sprinkler units to be hereinafter described.

Each pipe 24 is provided with a valve 25, said valve having a shaft 26 upon which is mounted a wing 27, said wing having an arched shape as clearly shown in Fig. 4. Located immediately below each of the wings 27 is a nozzle 28 mounted on one of the branch pipes 23.

As will be evident from the above construction, when the valve 21 is opened, as in case of a general fire all over the building, water will flow up through the auxiliary pipe 20 and into the branches 23. It will then pass out through the nozzles 28, which are so located as to cause a jet of water to impinge at high velocity upon the wings 27 of the valves 25. The force of the water jets will cause the wings 27 to rotate clockwise, opening the valves 25 and permitting water from the main feed pipe 19 to flow into the pipes 24 leading to the sprinkler units in the separate rooms of the building.

In case of a local fire in one room, the valve 21 will be left closed and the wing 27 of the valve 25 corresponding to said room will be operated manually, and in this manner only that particular room will be sprinkled.

The sprinkler units for spraying water upon the fire, and which are adapted to be

located in the separate rooms of the building, will now be described. Each of the sprinkler units comprises a hollow chamber 29 adapted to be suspended from a pipe 30 depending from the ceiling of the room where it is located. The chamber 29 may be spherical or any other desired shape, but as herein illustrated is preferably formed in the shape of an octahedron having six corners, five of which are shown in Fig. 1. The top corner 31 of the chamber 29 is flattened and is connected to the suspending pipe 30. The four side corners 32 and the bottom corner 33 of the chamber are also flattened and are provided with shafts 34 which serve as bearings for propellers 35.

A top propeller 36 similar to the propellers 35 is mounted to rotate about the pipe 30, said propeller being located below a bracket 37^a surrounding said pipe and attached to the ceiling of the room. The bearing shafts 34 are provided at their ends with slotted heads to permit said shafts to be readily manipulated with a screw driver or other suitable tool.

The propellers 35 and 36 are adapted to be actuated by water jets emerging from a series of nozzles 37, mounted in elbows 38 screwed into the faces of the chamber 29 adjacent said propellers. The nozzles 37 are mounted parallel to the planes of the faces of the chamber and are preferably directed at a point about two-thirds out from the centre to the rim of the propellers.

In operation when any one of the valves 25 is opened, either automatically or by hand, water will flow up through the pipe 24 and downwardly through the pipe 30 into the hollow chamber 29. The chamber 29 will rapidly fill, and water will then flow out through all of the nozzles 37. The six streams of water from the nozzles 37 will impinge upon the propellers 35 and 36, and will be broken up thereby and thrown from the six different corners of the hollow chamber 29 throughout all parts of the room, completely wetting the ceiling and walls of the room and soaking the burning material.

While there has been disclosed in this specification one form in which the invention may be embodied, it is to be understood that this form is shown for the purpose of illustration only, and the invention is not to be limited to the specific disclosure but may be modified and embodied in various other forms without departing from its spirit. In short, the invention includes all the modifications and embodiments coming within the scope of the following claims.

Having thus described the invention, what is claimed as new, and for which it is desired to secure Letters Patent, is:

1. In a fire extinguishing system for a building, a source of water supply, a water feed pipe and an auxiliary valve-controlling pipe connected to said source of water supply, a plurality of sprinkler units connected to said feed pipe, hand-operated valves for controlling the flow of water from said feed pipe to said sprinkler units respectively, said valves having operating members, nozzles on said auxiliary pipes in alinement with said operating members, said valves being simultaneously operated by a plurality of water jets from said nozzles when water is admitted to said auxiliary pipe. 65

2. In a fire extinguishing system for buildings, a main supply pipe, a feed pipe 80 and an auxiliary pipe connected to said supply pipe, each of said pipes having a branch pipe on each floor, said branch pipes being adjacent to each other, one of said branch pipes on each floor leading to sprinkler units located in the individual rooms, valves for said sprinkler units, and the other branch pipe having a series of nozzles for delivering jets of water to operate said valves simultaneously when the water is permitted 90 to flow into said auxiliary pipe. 95

3. In a fire extinguishing system for a building, a source of water supply, a plurality of sprinkler units, a plurality of pipes for connecting said source of water supply to said sprinkler units, each of said pipes having a hand-operated valve for controlling the flow of water from said source of water supply to its respective 100 sprinkler unit, each valve having a vane-shaped operating member, and water jet means in alinement with said operating members, and connected to said source of water supply for automatically and simultaneously opening a plurality of said valves. 105

4. In a fire extinguishing system for buildings, a main supply pipe, a vertical feed pipe and a vertical auxiliary pipe connected to said supply pipe, each of said vertical pipes having a horizontal branch pipe on each floor, said branch pipes being adjacent to each other, one of said branch pipes on each floor leading to sprinkler units located in the individual rooms, valves for said sprinkler units, and the other branch pipe having a series of nozzles for delivering jets of water to operate said valves simultaneously when the water is permitted 110 to flow into said auxiliary pipe. 115

In testimony whereof, I have affixed my 120 signature to this specification.

VITO GLISCE.
